Patented July 9, 1974

232,036

ANIMAL HABITAT

Allan H. Willinger, New Rochelle, and Albert J. Dinnerstein, Brooklyn, N.Y., assignors to Metaframe Corporation, Maywood, N.J.

Filed June 28, 1972, Ser. No. 267,149

Term of patent 14 years

Int. Cl. D30—06

U.S. Cl. D30—42

FIG. 4

FIG. 1

FIG. 2

FIG. 3.

FIG. 5

FIG. 1 is a front elevational view of an animal habitat, showing our new design;

FIG. 2 is an elevational view of one side thereof;

FIG. 3 is an elevational view of the other side thereof;

FIG. 4 is a rear elevational view thereof; and

FIG. 5 is a top plan view thereof.

We claim:

The ornamental design for an animal habitat, substantially as shown.
